CLAIM

The ornamental design for a hearing device, as shown and described.

DESCRIPTION

FIG. 1 is a top perspective of a hearing device;

FIG. 2 is a side view thereof;

FIG. 3 is a front perspective view thereof;

FIG. 4 is a bottom perspective view thereof;

FIG. 5 is bottom view thereof;

FIG. 6 is another bottom perspective view thereof;

FIG. 7 is a side perspective view thereof;

FIG. 8 is another top perspective view thereof; and,

FIG. 9 is another side perspective view thereof.

The broken lines shown in FIGS. 1, 4, 5, 6, and 8 illustrate

a boundary line that forms no part of the claimed design.
